United States Patent Office.

JOHN C. McCARTHY, OF NEW YORK, N. Y.

Letters Patent No. 96,457, dated November 2, 1869.

IMPROVEMENT IN HORSE-POWER ENGINES FOR EXTINGUISHING FIRES.

The Schedule referred to in these Letters Patent and making part of the same.

To all whom it may concern:

Be it known that I, JOHN C. McCARTHY, of the city, county, and State of New York, have invented a new and improved Horse-Power Fire-Engine; and I do hereby declare that the following is a full, clear, and exact description thereof, which will enable others skilled in the art to make and use the same, reference being had to the accompanying drawings, forming part of this specification, in which—

Figure 1 represents a front elevation of my improved horse-power fire-engine.

Figure 2 is a plan or top view of the same.

Figure 3 is a side elevation of the same.

Similar letters of reference indicate corresponding parts.

This invention relates to a new manner of constructing fire-engines with a view of facilitating their operation where man or steam-power cannot be readily obtained.

The invention consists in the application of an endless apron or other power to a fire-engine, so that horses on the engine or near it may operate its pump-work for extinguishing fire.

In suburban and country places, where engines could not be kept, and where the men may be employed on the fields, such an engine will be of great service, as one man, with one or two horses, can keep it in successful operation.

In the drawing—

A represents the truck or body of the engine.

B is the pump on the same.

C is the endless apron, for the horse to travel on, for operating the pump, by means of a crank-shaft, C, and piston-rod D.

The carriage may have vertical side plates, E, and a folding back plate, F, which latter, when let down, as in fig. 3, will serve as an inclined plane, for the horses to reach the apron.

The engine is drawn to the place of conflagration in the ordinary manner, and is then connected with the water, and can then be set in operation by the horses which conveyed it to the fire.

Having thus described my invention,

I claim as new, and desire to secure by Letters Patent—

1. The combination of the endless apron, the crank-shaft and piston, and the pump, all being arranged upon the truck A, as and for the purpose specified.

2. A carriage-frame, provided with the folding plate F, to turn down, and form a pathway for the horse to the endless apron, in the manner set forth.

JNO. C. McCARTHY.
